UNITED STATES PATENT OFFICE.

WILLIAM H. DE LOACH, OF KIRBY SPRINGS, GEORGIA.

WATER-WHEEL.

SPECIFICATION forming part of Letters Patent No. 231,411, dated August 24, 1880.

Application filed February 19, 1880.

To all whom it may concern:

Be it known that I, WILLIAM HENDERSON DE LOACH, of Kirby Springs, in the county of Bryan, in the State of Georgia, have invented 5 certain new and useful Improvements in Water-Wheels, of which the following is a full, clear, and exact description, reference being had to the accompanying drawings illustrating the same.

10 The object of my invention is to provide a cheap, durable, and effective water-wheel for use in a small head of water, and where but simple power is required.

The invention consists in a casing or box 15 having a spiral flume with the slightest inclination and wide stand highest at its receiving end, and gradually but rapidly increasing in its inclination toward, and as gradually and rapidly diminishing in its width and height at, its 20 discharging end, the said flume having its inclination in horizontal planes intersected by a central conical spiral orifice in said casing, which forms the seat for the conical shaft of the wheel, and serves to contract the spiral 25 flume, whereby the water is so introduced and controlled as to flow uniformly and overcome backlash. The casing, with its flume and shaft-seat, is hewn or dug out of solid timber, in order to effect solidity and simplicity of parts.

30 The invention further consists in the combination, with the casing, its flumes, and conical-shaft seat, of a wheel and its conical shaft, the edges of which shaft extend to the inner edges of the buckets, and thereby the surface 35 of said shaft acts as a water-shed to direct the fall into the buckets of such wheel.

The invention further consists in the details of construction of said wheel and casing, as hereinafter claimed.

40 In the drawings hereinbefore referred to, Figure 1 is a transverse section of my water-wheel and its casing, with the shaft in elevation. Fig. 2 is a top-plan view of the wheel detached. Fig. 3 is an elevation of the wheel, 45 partly broken away to show the buckets, and with half of the casing removed; and Fig. 4 is a bottom-plan view of the casing.

The letter A designates a suitable frame-work, upon which my wheel is arranged. Upon 50 this frame-work may be rigidly fixed the half B of a casing or box, made from solid wood,

and in this portion is arranged the water-gate or flood-gate a. The casing, with its flood-gate or water-gap a, is arranged in immediate connection with a fall or dam. Loosely connected to this portion B by dowel-pins b is the removable portion C of the casing, which is driven tightly against the portion B by wedge c, backed by posts d on the frame. I describe this construction particularly, as it is the simplest, cheapest, and most durable to me known but do not limit my invention thereto.

The water-gap a is of the same width as the buckets, and is open at the top and rear of the casing, so as to receive the full volume of water. A gate may or may not be used in it, a deemed advisable.

Each half of the casing is made with a central semicircular opening, which, when the two parts are brought opposite each other form a circular bearing, D, for the wheel-shaft. From a short distance below the edge of this opening the casing is cut away conically toward its bottom to form a conical seat, D', for a tapering shaft attached to the wheel, as herein after specified. Starting from a point opposite the inlet of the water-gap in the interior of the portion C of the casing, the timber is dug out to a line even with the top of the water-gap and in width extending from the point 1 in line with the outer edge of said gap to the point 2 on the edge of the shaft-opening. Taking the center of the shaft-opening as center, a circle is described of a diameter equal to the diameter of the wheel between the inner edges of its rim, and the digging out of the casing is continued to form a flume, E, with its periphery or outer wall on this circle and extending to the conical shaft-opening internally.

The excavating of the flume E proceeds on horizontal planes of decreasing altitude intersected vertically by the shaft-opening, and at the flume proceeds about this opening its width and height are gradually diminished, and at the same time its inclination increased until it ends in the part B opposite its starting-point and at a distance therefrom equal to the width of two buckets of the wheel. There is thereby left solid timber or a wall, 4, flush with the bottom of the casing, extending from a line between the points 1 2 to the discharge end.

the flume, for a purpose presently mentioned.

It will be noticed that the spirality in one erection of the flume is due to its being intersected by the conical shaft-bearing, and in the other to its inclination.

F is the shaft of the wheel, made tapering conical within the casing, and fitting snugly in the conical bearing or seat D'. The lower end of this shaft is made with a polygonal projection, e, upon which the wheel G is secured.

The shaft and wheel are supported from below by an adjusting or compensating lever, f, carrying a step, g, upon which the nib h of the shaft rests. The shaft is also made of timber.

The wheel G, with its buckets, is hewn from timber, and is usually about four inches thick, and bound with metal i, after the manner of putting on wheel-tires.

The buckets k are chiseled out of the face of the wheel in the intersecting planes of longitudinal and transverse vertical ellipses, their receiving ends l being at about an angle of thirty-five degrees to the axis of rotation, and sick, and their discharging ends m tapering to an edge on the horizontal plane of the bottom of the wheel. At the junction of the buckets with the rim n the curve o is upward on the face of the bucket, widest at the upper or entrance end, and gradually more abrupt until lost at the discharge end. This curve directs the water into the bucket properly and removes the objectionable angles that could otherwise exist.

In operation, the water coming in at the gap a falls upon the face of the wheel into the buckets and flows through the flume. It exerts its force upon all of the buckets except those under the timber at 4, and in a fourteen-bucket wheel twelve buckets will be in the water and two under the timber at 4. By this provision the water is most fully utilized and the effectiveness of the wheel enhanced, for there is constantly presented to the incoming water an empty bucket. The conical shaft acts as a water-shed to direct the water into the buckets, and causes the utilization of its entire force, and the construction of the flume and buckets prevents dead water and obviates backlash—ills that prevail very extensively in water-wheels.

I have obtained entirely satisfactory results

from a water-wheel of this construction with the wheel arranged directly under the pier or water-head, and with from three to seven feet 55 of water, and my wheel is designed for use with small water-powers of such character. It is cheap, easily repaired, not liable to easy derangement, and very durable. There are no castings, no joints to break, loosen, or wear, 60 no movable buckets, and nothing that an ordinary country millwright may not make or alter with the simplest tools. The metal rim i serves to strengthen the wheel and prevent its bursting or being chipped or abraded, and 65 may be applied in the same manner as a tire to a carriage-wheel.

What I claim is—

1. A water-wheel having a solid wood casing constructed with a conical-shaft seat and 70 a spiral inclined flume, substantially as and for the purpose described.

2. The casing or box of a water-wheel having a spiral flume with the slightest inclination and widest and highest at its receiving 75 end, and gradually but rapidly increasing in its inclination, and as gradually and rapidly diminishing in its width and height, at its discharging end, and intersected vertically by a conical seat for the wheel-shaft, which serves 80 to contract the spiral flume, whereby the water may be introduced and controlled so as to flow uniformly and overcome backlash, substantially as specified.

3. The combination of the casing, the flume, 85 and conical-shaft seat therein with a wheel and a conical shaft, the said conical shaft terminating at the inner edges of the buckets of the wheel, substantially as specified.

4. A water-wheel the peripheral edges o of 90 the buckets of which are curved upwardly, substantially as shown and described.

5. The casing of a water-wheel having a flume and wall, 4, interposed between the receiving and discharging ends of such flume, 95 substantially as and for the purpose described.

To the above specification of my invention I have signed my name this 4th day of August, A. D. 1879.

W. H. DE LOACH.
